UNITED STATES PATENT OFFICE

2,480,477

APPARATUS FOR REMOVING FORMS FROM
CONCRETE BLOCKS

Forrest H. Jones, Rockport, Wash.

Application August 13, 1946, Serial No. 690,113

5 Claims. (Cl. 25—120)

1 My invention relates to forms for producing concrete blocks or the like and more particularly to apparatus to remove the form from the finished block.

The object of my invention is to provide an apparatus to be placed between the mold and the material to be formed therein and adapted to be filled with compressed air to lift and remove the form from the finished product.

Other objects of the invention may appear in the following specification describing my invention with reference to the accompanying drawing illustrating a preferred embodiment of my invention.

It is, however, to be understood that my invention is not to be limited or restricted to the exact construction and combination of parts described in the specification and shown in the drawing, but that such changes and modifications can be made which fall within the scope of the claims appended hereto.

In the drawing

Figure 1 is a top view of an apparatus according to my invention.

Figure 2 is a sectional view taken on line 2—2 in Figure 1, the apparatus being shown in deflated position.

Figure 3 is a sectional view similar to Figure 2, but showing the apparatus in inflated position and showing a connection between the apparatus and a pipe line for compressed air, and

Figure 4 is an exploded sectional detail view of a fragment of the upper section of the apparatus and the lower section thereof, showing a compressed air outlet in the upper section and a guide pin fitting in said outlet and rigidly mounted on the lower section, the two sections being made from a center layer of textile and two layers of rubber covering the center layer.

Referring now in detail to the drawing the apparatus according to my invention has preferably a circular outline. In Figures 2 and 3 it is shown as being made from automobile body metal or the like. It has a circular upper section 10, on which an upwardly extending hollow boss 11 is either formed integrally or fastened rigidly, as by welding. The boss is located centrally of the circular section. A pipe 12 is located in and extends through the hollow boss 11 and through the top or upper section 10. It is securely fastened in position by means of a washer 13, firmly attached to the underside of the upper section 10, for instance, by welding. The upper end of the pipe 12 is provided with an outside thread 14 adapted to be threadedly engaged by a coupling nut 15 on

2 a hose 16 or the like connected with a source of compressed air (not shown).

A plurality of holes 17 is provided in the upper section 10, and these holes are arranged at equal distances from the centrally located pipe 12 and at equal angular distances from each other.

A lower section 18 has the same shape and size as the top section 10 and the two sections are securely welded together at their circumference, so that the seam is air-tight.

A plurality of guide plugs 19 are securely fastened onto the upper surface of the lower section 18 and are located thereon, so that they correspond with the location of the holes 17 in the upper section 10. The plugs are finished to fit slidably in said holes.

In Figure 4 an upper section 20 is illustrated consisting of an inner layer 21 made from textile fabric and two outside layers 22 and 23 respectively made from rubber and covering the inner layer. The lower section 24 illustrated in Figure 4 is also made of an inner textile layer 25 and two outside rubber layers 26 and 27 respectively covering the inner textile layer 25.

In the center of the upper section 20 an upwardly extending pipe (not shown) is rigidly embedded. This pipe corresponds to the pipe 12 shown in Figures 2 and 3 and is adapted to be engaged by a coupling nut similar to the nut 15 shown in Figure 3.

A plurality of holes 28, corresponding to the holes 17 in Figure 3, is provided in the upper section 20 and the edges of these holes are protected against damage by thin steel washers 29 embedded in the textile layer 21 or by wales provided in said layer.

In the lower section 24 frustoconical countersunk washers 30 are provided. Through each countersunk washer a countersunk screw 31 extends upwardly, and a plug 32 is adapted to be engaged threadedly by and securely held on each screw. The screws are located so that the plugs 32 fit slidably into the holes 28 in the upper section 20, when the two sections are connected with each other on their circumference to form an air-tight unit.

In use the above described apparatus is arranged on a form 33, in which a concrete block 34 or the like is to be formed, before the concrete is poured. After the block 34 is finished and ready for removal, compressed air is permitted to flow into the apparatus, expanding it, as shown in Figure 3 and separating the form from the block easily and readily.

While my invention has been described in use

for removing cement blocks from the forms or vice versa, it is to be understood that it can also be used for stripping forms from concrete walls and all other types of concrete constructions.

Having described my invention I claim as new and desire to secure by Letters Patent:

1. An apparatus for stripping a form from a molded article by fluid pressure, comprising an expansible member adapted to be interposed between an inner surface of a form and the molding material contained therein, said member comprising inner and outer coextensive sections of impervious sheet material disposed in superposed relation, said sections including marginal portions hermetically sealed together, means for introducing fluid under pressure between said sections to expand said member, one of said sections being formed with at least one aperture therethrough, a plug carried by the other section and extending through said aperture, said plug being formed to have a close sliding fit in said aperture, and said plug being adapted to be completely withdrawn from said aperture after predetermined expansion of said member, whereby to relieve fluid pressure therein.

2. An apparatus for stripping a form from a molded article by fluid pressure, comprising an expansible member adapted to be interposed between an inner surface of a form and the molding material contained therein, said member comprising inner and outer coextensive sections of impervious sheet material disposed in superposed relation, said sections including marginal portions hermetically sealed together, means for introducing fluid under pressure between said sections to expand said member, said outer section being formed with at least one aperture therethrough, an inwardly directed plug carried by said inner section and extending through said aperture, said plug being formed to have a close sliding fit in said aperture, and said plug being adapted to be completely withdrawn from said aperture after predetermined expansion of said member, whereby to relieve fluid pressure therein.

3. An apparatus for stripping a form from a molded article by fluid pressure, comprising an expandible member adapted to be interposed between an inner surface of a form and the molding material contained therein, said member comprising inner and outer coextensive sections of sheet 5

metal disposed in superposed relation, said sections including marginal portions hermetically sealed together, and means for introducing fluid under pressure between said sections to expand said member.

7

4. An apparatus for stripping a form from a molded article by fluid pressure, comprising an expandible member adapted to be interposed between an inner surface of a form and the molding material contained therein, said member comprising inner and outer coextensive sections of impervious textile sheets disposed in superposed relation, said sections including marginal portions hermetically sealed together, and means for introducing fluid under pressure between said sections to expand said member.

5. An apparatus for stripping a form from a molded article by fluid pressure, comprising an expansible member adapted to be interposed between an inner surface of a form and the molding material contained therein, said member comprising inner and outer coextensive sections of impervious sheet material disposed in superposed relation, said sections including marginal portions hermetically sealed together, means for introducing fluid under pressure between said sections to expand said member, one of said sections being formed with at least one aperture therethrough, annular means reinforcing said aperture, a plug slidable in said aperture, means detachably connecting said plug to the other section, and said plug being adapted to be completely withdrawn from said aperture after predetermined expansion of said member, whereby to relieve fluid pressure therein.
